UNITED STATES PATENT OFFICE.

FREDERICK W. REESE, OF PARIS, ILLINOIS.

BROOM-CORN CLEANER.

SPECIFICATION forming part of Letters Patent No. 505,128, dated September 19, 1893.

Application filed August 2, 1887. Serial No. 245,943. (No model.)

To all whom it may concern:

Be it known that I, FREDERICK W. REESE, a citizen of the United States, residing at Paris, in the county of Edgar, State of Illinois, have 5 invented certain new and useful Improvements in Broom-Corn Cleaners, of which the following is a specification, reference being had therein to the accompanying drawings.

This invention relates to certain new and 10 useful improvements in broom corn cleaners, of that class disclosed in the patent to Anderson, No. 413,883, dated October 29, 1889; having for its object among others to provide simple means whereby the soot and dust from 15 the cylinders is conducted away and the dust caught and carried away from the refuse bin as it floats therefrom. To this end I arrange an exhaust fan and up-take above the meeting lines of the cylinders and over the refuse 20 bin as more fully hereinafter disclosed.

Other objects and advantages of the invention will hereinafter appear and the novel features thereof be particularly pointed out in the claims.

25 Referring to the drawings: Figure 1 is a side elevation of a broom corn cleaner constructed in accordance with my invention. Fig. 2 is a similar view showing the opposite side of the machine, certain portions being 30 removed, in Figs. 1 and 2 (as for example, collars G¹⁰) for the purpose of clearer illustration. Fig. 3 is a transverse section taken on the line x x of Fig. 1 showing the interior of the machine. Fig. 4 is a detailed side elevation hereinafter referred to.

Similar letters of reference indicate similar parts throughout the drawings.

A represents, in this instance, a rectangular casing provided with openings, A', A², respectively at its front and rear ends, and with a depending hopper, A³, at one corner thereof. A door, A⁴, is provided at one side of the machine, whereby access to the interior of the case and its internal mechanism is afforded.

45 Mounted upon a shaft, B, passing through the lower portion of the front of the machine is a drive-pulley, B', and adjacent thereto upon said shaft, is a master-gear, B². At the opposite end of the shaft B, is mounted a 50 sprocket wheel B³. Journaled in bearings C', C², at the side of the casing and directly in line with, and at a right angle to, the shaft

B, is a vertical shaft C, carrying beveled gears, C³, C⁴, C⁵, the lower one, C⁵, meshing with and receiving motion from the master gear B², and thus imparting a rotary motion to the vertical shaft C, and the gears; C³, C⁴, meshing with similar gears D', D², projecting from the casing and mounted upon the shafts of the upper and lower cylinders D, D¹, respectively, which are provided with teeth, said cylinders being arranged diagonally across the casing and above the hopper A³, and journaled in bearings, D³, D⁴, the former being formed in a post D⁵ and the latter in a casting or 60 bracket D⁶, secured to the frame work of the casing and projecting therein.

Projecting from the front of the casing and in a line with the opening A', is a frame E, supporting at its outer end a shaft E', and at 70 its rear end a shaft E², passing outside of the casing and carrying a sprocket-wheel E³, and a gear E⁴. Pulleys E⁵, are mounted on the shafts E' E², those upon the shaft E², being rigid therewith and those upon the shaft 75 E', being mounted loosely thereon. Belts or aprons pass over the pulleys E⁵. The framework E, is also provided with an intermediate shaft F, upon which is mounted a sprocket-wheel F', over which runs a continuous toothed 80 or comb belt F². This belt passes through the machine on a line with the space between the cylinders D, D¹, and its rear end extends beyond and through the rear opening A³, in the casing and over a sprocket-wheel G, 85 mounted upon a shaft G' extending across the rear of the machine and supported in brackets or bearings G², projecting rearwardly from each side of the rear end of the machine. At one end of the shaft G', is a sprocket G³, over 90 which an endless chain passes and connects the said sprocket with the sprocket E³, mounted on the shaft E². At the opposite end of the shaft G', is a small bevel gear G⁵, which meshes with a similar gear G⁶, mounted at 95 the side of the machine upon a shaft G⁷, journaled in bearings G⁸, said shaft being provided at its opposite end with a pulley G⁹.

Communicating with the bottom of the hopper A³ so as to receive the contents thereof, is 100 an elevator H, which is arranged at the side of the casing and may be projected to a desired point. Mounted upon the usual shaft H', within the elevator are the elevating belts

H^2 , and pulleys H^3 . A small pulley H^4 , is mounted at one side of the elevator upon the shaft H' , and a belt H^5 , connects the same with the pulley G^9 .

5 Mounted upon the top of the casing is a rotary blower I , which receives motion from a pulley I' , leading from which, and to a pulley I^2 , mounted upon the upper end of the vertical shaft C , is a belt I^3 .

10 A shaft J , carrying a toothed wheel J' , upon its inner end, and a sprocket wheel J^2 , upon its outer end, is mounted in bearings J^3 and is arranged back of the belts E^6 , the toothed wheel thereof being directly over and in line

15 with a toothed or comb belt F^2 . A guard, or guide K , is secured to the framework of the casing and extends longitudinally therewith and in line with and adjacent to the toothed or comb belt F^2 .

20 The advantage of the toothed wheel, J' , is the novel species of packing action introduced by the same, inasmuch as the straw is grasped from a point more forward than the teeth on the belt, into which the said wheel 25 is destined to carry said brush. The effect of this forward grasp of the teeth on the wheel, is to pack the brush in little bundles in between the teeth on the belt, and thus hold the same much more securely, when said 30 bundles are carried under the guide, than would be the case, were the brush not so compacted.

The operation of my invention is as follows:—The brush being laid upon the belts 35 E^6 , which are in motion and are driven through the medium of the gear E^4 , meshing with the gear B^8 , mounted upon the shaft B , which in turn is driven by the driving pulley B' , is carried through the opening A' , into 40 the machine and passes under the toothed wheel J' , which presses them down between the moving toothed belt F^2 . The belt F^2 , receives its motion through the sprocket G , shaft G' , sprockets E^8 , chain G^4 , and gear 45 B^8 . After the brush has been packed down between the teeth of the belt F^2 , said belt carries the same on under the guard K . The heads or brush part have by this time reached the toothed rollers, which receive 50 motion from the vertical shaft C , and pass between the same, during which operation the seed are torn or knocked from the brush and fall into the hopper A^8 , where they are taken up by the elevator and delivered into 55 any receptacle provided for their reception. The dust and other foreign matter are drawn up through an opening i^x by the rotary blower

I, and, if the machine be operated out doors is blown up over the heads of the operators, or, if it be indoors, it may be discharged through pipe I^{xx} or any suitable conveyer to the outside. As the seed are stripped from the stems (which is accomplished by the time they have passed through the diagonally arranged cylinders), said stems are carried through and delivered into any receptacle or upon the ground at the rear of the machine. The pulley J^2 is above the sprocket chain G^4 , and rests thereon, and by this means the shaft J and toothed wheel J' are given motion.

Any suitable elevator may be employed for raising the seed from the hopper, and in this instance, I secure a series of transverse blades H^6 to the endless belts H^2 , which blades catch the seed as they fall from the brush and elevate them to the top of the elevator where they are delivered.

For the purpose of extricating or raising the stems of the brush from the teeth of the belt F^2 , after they have passed through the cylinders, I provide collars, G^{10} , at each side of the sprocket G , upon the shaft G' . These collars being greater in circumference than the sprocket G , upon which the toothed belt runs, will raise the stems from between the teeth, and drop the same therefrom.

Having described my invention and its operation, what I claim is—

1. In a machine of the class described and in combination with the cylinders and feed mechanism thereof, a casing provided with front and rear openings and arranged to encompass the cylinders and to permit of the introduction and egress of the material to be operated upon, an exhaust apparatus for withdrawing the dust and similar refuse collecting within the cleaning compartment of the machine, and an elevating mechanism, all substantially as and for the purposes described.

2. The combination with a pair of diagonally-arranged cylinders and the feed mechanism, of a casing provided with front and rear openings, an elevator and an exhaust mechanism and up-take located above the meeting line of the cylinders and over the refuse collecting bin, substantially as and for the purpose specified.

In testimony whereof I affix my signature in presence of two witnesses.

FREDERICK W. REESE.
